[57] CLAIM

The ornamental design for a seat, as shown and described.

DESCRIPTION

FIG. 1 is a right front perspective view of a seat showing my new design;

FIG. 2 is a left rear perspective view thereof;

FIG. 3 is a right side elevational view, the left side being a mirror image thereof;

FIG. 4 is a front elevational view thereof; and,

FIG. 5 is a right front perspective view of a second embodiment of my new design shown in FIG. 1.

FIG. 1

FIG. 3

FIG. 2
